B. C. TRAVIS & M. BARUCH,
FLANGE TRIMMER.
APPLICATION FILED FEB. 14, 1916.

1,185,557.

Patented May 30, 1916.

UNITED STATES PATENT OFFICE

BERTRAM C. TRAVIS AND MILTON BARUCH, OF LOS ANGELES, CALIFORNIA, ASSIGNEES
TO LLEWELLYN IRON WORKS, OF LOS ANGELES, CALIFORNIA, A CORPORATION OF
CALIFORNIA.

FLANGE-TRIMMER.

1,185,557.

Specification of Letters Patent.

Patented May 30, 1916.

Application filed February 14, 1916. Serial No. 78,316.

To all whom it may concern:

Be it known that we, BERTRAM C. TRAVIS, a subject of the King of the United Kingdom of Great Britain and Ireland, and MILTON BARUCH, a citizen of the United States of America, both residing at Los Angeles, in the county of Los Angeles and State of California, have invented a new and useful Flange-Trimmer, of which the following is 10 a specification.

Our invention relates to the art of trimming the flanges which are commonly used in boiler and pipe works. It is common practice to forge these flanges in the rough, 15 and then secure them on the face plate of a lathe, trimming off the edges of the flanges in a true circle.

The principal object of our invention is to provide a device by which these flanges 20 may be quickly and accurately trimmed in rotary shears.

A further object of the invention is to provide such a device which can be adjusted to suit different internal diameters and different rim diameters of flanges, and further to provide means whereby the device can be set for a certain size of flange and may be used continuously for cutting flanges of that size without individual adjustment.

30 Further objects and advantages will be made clear hereinafter.

In the drawings, which are for illustrative purposes only: Figure 1 is a perspective view of a finished flange. Fig. 2 is a side 35 elevation of a portion of a rotary shear with our invention applied thereto, a portion thereof being shown in section to better illustrate the internal structure. Fig. 3 is a plan view of the work holding portion 40 of the apparatus shown in Fig. 2.

In the drawings, a shear frame 11 is provided in which shafts 12 and 13 are journaled, said shafts being connected by gears 14 and 15 and being driven by any suitable 45 means not shown. Secured on the forward end of the shaft 12 is an upper cutter 16, and similarly secured on the shaft 13 is a lower cutter 17, cutter 16 overlapping the cutter 17, the parts 11 to 17 being a standard 50 form of tool found in practically every boiler shop. For the purpose of adapting this tool to the cutting of flanges, we provide a bracket 21 which is secured to the frame 11 by means of bolts 22 or by any 55 other convenient means. A slide 23 is

mounted in guides 50 so that it will slide along a line parallel to the axis of the shaft 13, the position of the slide 23 along this line being adjusted by a screw 24 which is rotatably secured in the slide 23 by a plate 60 25 and which is threaded at 26 in a bracket 27 which is fastened by means of bolts 28 to the bracket 21. A hand wheel 29 is provided on the end of the screw 24 to provide for ready adjustment of the slide 23. The 65 slide 23 is provided with two holes 30 and 31 in either of which may be fitted a center pin 32, this center pin comprising a central cylindrical portion 33, an upper portion 34 and a lower portion 35, the portions 34 and 70 35 being set eccentric to each other and to the central portion 33. Rigidly secured on the central portion 33 is a feed lever 36. A series of variable centers 41 are provided, these centers slipping over and turning 75 freely on the upper portion 34 of the eccentric pin 32 and being provided with a lower flange 42 and a central cylindrical portion 43. A number of centers 41 are provided 80 having cylindrical portions 43 of the proper size to fit inside the flanges 44 which it is desired to trim, these flanges 44 consisting of a cylindrical portion 45 and a rim 46.

The method of operation of the invention is as follows: The eccentric pin 32 being 85 placed either in the hole 31 or in the hole 30, depending on the size of flange which it is desired to cut, the proper size of center 41 is selected to fit inside the flange, this center being placed on the portion 34 of the pin 90 32, turning freely thereon. The flange 34 is then placed over the center in the position shown in Fig. 2, and the hand wheel 29 is manipulated to move the slide 23 in or out to suit the diameter to which it is desired to cut the rim 46. The feed lever is normally in the position shown at A in Fig. 3. The cutters 16 and 17 being rotated, the rim 46 is forced between the cutters 16 and 17 and a light cut is started thereon. The 100 operator then forces the lever 36 from the position A to the position B, the cutters 16 and 17 cutting continuously during the time that the lever 35 is being moved. The cutters 16 and 17 are thus allowed to cut a 105 comparatively thin shaving from the end of the rim 46, the final diameter being determined by the position of the slide 23.

It will be noted that the screw 24 forms the primary adjusting means for adjusting 110

the position of the slide 23, and the lever 36 forms a secondary adjusting means for quickly and powerfully forcing the ring 46 into engagement with the wheels 16 and 17.

5 We claim as our invention:

1. A flange trimmer, comprising a pair of circular rotating cutters arranged in shearing relation, a slide mounted to move away from or toward said cutters, a center pin mounted on said slide, a removable center mounted on and turning freely on said center pin and adapted to support the flange to be trimmed, primary adjusting means for forcing said slide toward said cutters, and secondary adjusting means for forcing said center pin toward said cutters without changing the position of said slide.
2. A flange trimmer, comprising a pair of circular rotating cutters arranged in shearing relation, a slide mounted to move away from or toward said cutters, a center pin mounted on said slide, said pin having an upper cylindrical portion and a lower cylindrical portion, said upper cylindrical portion having its axis eccentric with relation to the axis of said lower cylindrical portion and said lower cylindrical portion being journaled to turn freely in said slide, a removable center mounted to turn freely on the upper cylindrical portion of said center pin and of such a size and shape as to receive and support the flange to be trimmed, screw means for adjusting the position of said slide with relation to said cutters, and a feed lever rigidly secured to said center pin on a cylindrical portion of said pin located between said upper cylindrical portion and said lower cylindrical portion by which said center pin may be turned in said slide to throw the rim of said flange between said cutters.
3. A flange trimmer, comprising a pair of circular rotating cutters arranged in

shearing relation, a slide mounted to move away from or toward said cutters, a center pin mounted on said slide, said pin having an upper cylindrical portion and a lower cylindrical portion, said upper cylindrical portion having its axis eccentric with relation to the axis of said lower cylindrical portion and said lower cylindrical portion being journaled to turn freely in said slide, a removable center mounted to turn freely on the upper cylindrical portion of said center pin and of such a size and shape as to receive and support the flange to be trimmed, screw means for adjusting the position of said slide with relation to said cutters, and a feed lever rigidly secured to said center pin on a cylindrical portion of said pin located between said upper cylindrical portion and said lower cylindrical portion by which said center pin may be turned in said slide to throw the rim of said flange between said cutters.

4. A flange trimmer, comprising a pair of circular rotating cutters arranged in shearing relation, a slide mounted to move away from or toward said cutters, a center pin mounted on said slide, means for securing the flange to be trimmed on said center pin, primary adjusting means for forcing said slide toward said cutters, and secondary adjusting means for forcing said center pin toward said cutters without changing the position of said slide.

In testimony whereof, we have hereunto set our hands at Los Angeles, California, this 7th day of February, 1916.

BERTRAM C. TRAVIS.
MILTON BARUCH.
